[57] **CLAIM**

The ornamental design for a garment pocket, as shown and described.

DESCRIPTION

FIG. 1 is a perspective view of a garment pocket showing my new design in use, the broken lines partially showing a garment being for illustrative purposes only and forming no part of the claimed design;

FIG. 2 is a front elevational view thereof;

FIG. 3 is a left side elevational view thereof;

FIG. 4 is a right side elevational view thereof;

FIG. 5 is a top plan view thereof;

FIG. 6 is a rear elevational view thereof;

FIG. 7 is a bottom plan view thereof; and,

FIG. 8 is a perspective view thereof shown in an open position, the broken lines showing a button stud and partially showing a garment being for illustrative purposes only and forming no part of the claimed design. The broken lines shown on the claimed article throughout the views are intended to represent conventional stitching.

FIG. 1

FIG. 2

FIG. 3

FIG. 4

FIG. 5

FIG. 6

FIG. 7

FIG. 8
